UNITED STATES PATENT OFFICE.

JAMES W. MONTGOMERY, OF THOMASVILLE, GEORGIA.

SINGLETREE.

Application filed June 7, 1922. Serial No. 566,520.

To all whom it may concern:

Be it known that I, JAMES WARREN MONTGOMERY, a citizen of the United States of America, residing at Thomasville, in the 5 county of Thomas and State of Georgia, have invented certain new and useful Improvements in Singletrees, of which the following is a specification.

My invention relates to single-trees 10 adapted for use on farming implements and wagons, both as a single-tree and as a breast yoke, and which is designed of metal so as to give it the maximum strength without unduly increasing its weight.

One object of my invention is to improve 15 the design and manner of attachment of the trace hooks, these being so arranged that while affording a secure attachment for the trace ring or link permit the latter to be attached and detached when the hook is swung into alignment with the single-tree, and moreover the back of the hook is disposed outwardly so as to avoid catching or injuring 20 plants or trees.

A further object is to simplify and improve 25 the type of draft hook which is adapted not only to swivel but is provided with reversely disposed hinged hook members which when lapped form a closed eye and 30 which are intended to open by a bodily swinging movement apart of the hooks, the importance of this arrangement being that in all positions of service the draft ring will 35 prevent any tendency on the part of the hook sections to open up.

My invention also comprises the novel details of construction and arrangements of parts, which are hereinafter described and 40 claimed and which in their preferred embodiment only are illustrated in the accompanying drawings, in which:—

Fig. 1 is a plan view of my improved 45 single-tree or breast yoke with the trace hooks shown in operating position.

Fig. 2 is an enlarged detail plan view of 50 part of the single-tree showing one trace hook and the draft hook in plan with the trace hook in its open position.

Fig. 3 is a rear elevation of Fig. 2.

Fig. 4 is a plan view of the single-tree 55 blank.

Fig. 5 is a detail view of the draft hook showing its lug in plan and the hook members opened out.

Similar reference numerals refer to similar parts throughout the drawings.

According to my invention as illustrated, I show the single-tree 1 formed of a bent metal plate. The plate tapers substantially and symmetrically from its center towards each end and the purpose of this is to enable the single-tree as formed to have gradually widening top and bottom plates as it approaches its center, and also to have the spacing between the top and bottom plates gradually increasing from each end to the center, thus giving an enlarged and an increased body of metal at the center of the single-tree which will give the maximum strength where needed. Into the center of the opening in the single-tree I introduce the attaching lug 2 for the draft hook. This lug is preferably a metal forging and for lightness is formed with wing-like ends 3 which are shaped to fit snugly between the top and bottom members of the single-tree and which are connected in position between same by rivets 4. I provide a central opening 5 in the lug which is adapted to receive the swivel shank 6 of the draft hook so as to 60 permit the latter to swivel therein. This shank is formed with an eye 7 which receives a bolt or rivet 8, by means of which the eyes 9 on the co-acting hook elements 10, 65 forming the draft hook, are pivotally connected to the shank eye on each side thereof. These draft hook members 10 are duplicate parts disposed with their hooks pointing in 70 opposite directions and so designed that when the hooks lap they form a closed eye 75 for the reception of the draft ring or like element 11 on the draft rigging (not shown). It will be observed that when the hook members stand in lapped position with the draft ring 11 engaged therein no slack- 80 ing or working of the draft rigging will have any tendency to open up the draft hook eye and release the draft rigging. The draft ring opposes any opening movement 85 of the hooks 10. The draft hook can be 90 opened up for the detachment of the draft ring only by swinging the draft ring around to the side so as to clear one of the hook members 10, whereupon the other hook member 10 can be swung up and the draft ring 100 can then be disengaged from the one member that was retaining it. It follows therefore that only by bringing the draft ring far around to one side it is possible to separate the members 10 sufficiently for the disengagement of the draft ring and in no ordinary usage of the single-tree would it be 105 110

possible for the draft ring to swing to that position. Therefore, when the draft ring is once engaged in the draft hook it cannot be accidentally disengaged though it can be 5 very readily and quickly disengaged when the operator desires, and this feature is of special importance when the single-tree is used on a wagon, where on going down hill the single-tree is loose and tends to become 10 disengaged from the whiffletree.

At each end of the single-tree between the upper and lower members thereof I interpose the eyes 12 of trace hooks 13, which eyes are offset to the same side of the shank as the 15 hook end 14. In other words, the trace hooks have very much the shape of the letter C with the hook end 14 having an inturned lug or shoulder 15 and being spaced from the rivet 16 which pivotally connects the 20 hook eye to the single-tree, so that it will just clear the end of the single-tree as it swings from open to closed position, and vice versa. The hooks stand in alignment with the single-tree when in open position 25 for permitting the engagement and disengagement of the trace ring. The shank of the hook in cross section is of such shape as to be adapted to be inserted in a chain link if desired and to this end the shank is made 30 flatter and wider than the ordinary trace hook which has a cross section too thick to be passed through an ordinary trace chain link. It will also be noted that I do not cut away or notch the ends of the single-tree, 35 this being unnecessary by reason of the widely offset position of the trace hook eye 12 which permits the trace hook end 14 to swing past the rear edge of the single-tree and to have its neck substantially closed 40 thereby without having to notch or weaken the single-tree. When the trace hook is

swung into alignment with the single-tree its neck is open for the engagement or disengagement of the trace ring or link and therefore I avoid the objection of having to pull the trace hook back through a half circle to bring it into position to release or engage the trace. When once the trace ring has been engaged in its hook and the latter has swung to its rear or operating position, the trace 45 ring will not become disengaged as only a wide lateral swing of the hook through approximately a 90° arc will make possible to engage or disengage a trace ring, and such a movement will not accidentally occur. 50

Though I have described with great particularity the details of the embodiment of the invention herein shown, it is not to be construed that I am limited thereto as changes in arrangement and substitution of 55 equivalents may be made by those skilled in the art without departing from the invention as defined in the appended claim.

Having thus described my invention, what I claim as new and desire to secure by Letters Patent, is:—

A single-tree formed of a bent metal plate having trace hooks mounted at its ends and having at its center a swivel lug mounted rigidly in the bend of the plate, a 70 horizontal swivel pin mounted to turn in the front end of said lug, the forward end of said pin being flattened and provided with an eye, a pair of lapped hooks having their ends flattened in a plane at right angles to the plane of the hook and perforated, and a pivot bolt connecting said hook ends to the 75 end of the swivel pin.

In testimony whereof I affix my signature.
JAMES W. MONTGOMERY.

Witness:

NOMIE WELSH.
